UNITED STATES PATENT OFFICE.

FREDERICK HOHLFELDER, OF CLEVELAND, OHIO.

DESIGN FOR A CHAPLET.

SPECIFICATION forming part of Design No. 25,303, dated March 31, 1896.

Application filed February 15, 1896. Serial No. 579,458. Term of patent 7 years.

To all whom it may concern:

Be it known that I, FREDERICK HOHLFELDER, a citizen of the United States, residing at Cleveland, in the county of Cuyahoga and State of Ohio, have invented and produced a new and original Design for Chaplets for Use in Metal Founding, of which the following is a specification, and, as shown in the drawings, forming a part thereof.

In the drawings, Figure 1 is a perspective view of a chaplet fashioned according to my design, the chaplet as shown in this figure having its lower end inclined away and the head turned forward to more clearly disclose the shape and appearance of the face of the head. Fig. 2 is a vertical sectional elevation of the top part of the chaplet and designed to clearly show the appearance of the projections on the head.

The leading and distinguishing feature of my design, as thus shown, is the head A, which in general outline resembles an ordinary disk with flat top and bottom sides and having a cylindrical stem B at its center. The head itself is circular and is distinguished by the ornamentation on the top surface and side thereof, said ornamentation consisting of substantially conical projections 2, which are numerously interspersed over the surface of the head.

What I claim is—

The design for a chaplet, substantially as shown and described.

FREDERICK HOHLFELDER.
